DEVICE FOR LONGITUDINALLY RESHAPING CORRUGATED WIRE SPRINGS

Svend G. Blumensaadt, Beachwood Village, Ohio, assignor to The Universal Wire Spring Company, Bedford, Ohio, a corporation of Ohio

Application September 18, 1951, Serial No. 247,109

1 Claim. (Cl. 140—89)

This invention relates to a device usable in the manufacture of wire springs shaped of zigzag bent or sinuously corrugated wire bent to zigzag shape in wire bending or corrugating machines designed to give the corrugated wire the desired number of corrugations per foot. Sinuously corrugated wire springs shaped from corrugated wire of the type referred to above develop in their resting surfaces under load either too stiff or too yielding areas caused by excessive or insufficient load counteracting torsional stresses in the loop connecting cross wires of the springs, a condition which can readily be avoided by spacing in these areas the loop-connecting cross wires differently from the general equal spacing of such cross wires in the resting surfaces for either locally increasing or decreasing the load counteracting torsional stresses in loop connecting cross wires of these areas.

The primary object of this invention is the provision of a practical, efficient device for changing in predetermined areas of corrugated wire springs the spacing of their loop-connecting cross wires for the purpose of varying the load counteracting torsional stresses in the loop-connecting cross wires of said areas.

Such a general object of the invention is attained by subjecting wire spring loops in certain predetermined areas of corrugated wire springs, by means of correlated shifting elements, to stresses adapted to change such loops and the spacing of the cross members connecting the loops to provide corrugated wire springs with areas differentiating in their number of corrugations per foot.

Another object of the invention, therefore, is the provision of a device of the type referred to above constructed to include correlated shifting elements adapted to engage in a predetermined area of a corrugated wire spring loops thereof, the elements arranged to be shifted with respect to each other for reshaping the said loops and the spacing of the cross members connecting these loops.

A further object of the invention is the provision of a device of the type described above in which the correlated shifting elements are mounted on and coupled with each other by a lazy tongs structure having its direction of movement controlled by guide means.

Still another object of the invention is the provision of a device of the type described above in which the correlated shifting elements are mounted on a lazy tongs structure having its central area rigidly supported and its opposite ends actuated upon by power-operated shifting means to symmetrically shift the shifting elements supported by the lazy tongs structure.

Still further objects and novel features of construction, combination and relation of parts by which the objects in view have been attained, will appear and are set forth in detail in the course of the following specification.

The drawings accompanying and forming part of the specification illustrate certain practical embodiments of the invention, but it will be apparent as the specification proceeds that the structure may be modified and changed

2

in various ways without departure from the true spirit and broad scope of the invention.

In the drawings:

Fig. 1 is a plan view of an apparatus constructed in accordance with the invention;

Fig. 2 is a fragmentary, longitudinal sectional view through the apparatus shown in Fig. 1, the section being taken on line 2—2 of Fig. 1;

Fig. 3 is a cross-sectional view taken on line 3—3 of Fig. 1;

Fig. 4 is a cross-sectional view taken on line 4—4 of Fig. 1;

Fig. 5 is a cross-sectional view taken on line 5—5 of Fig. 1;

Fig. 6 is a diagrammatic view of the hydraulic system actuating the apparatus; and

Fig. 7 is a fragmentary plan view of a sinuously corrugated wire spring embodying areas differentiating in the spacing of their loop-connecting cross members.

Referring now more particularly to the exemplified form of the invention shown in the drawings, reference numeral 2 denotes a wire spring squeezing fixture embodying an elongated base plate 3 mounted on ribs 4, which base plate has secured to its opposite ends symmetrically constructed cylinder hanger members 5, 5', each of which embodies a perforated vertical plate 6, 6', respectively, secured by screws 7 to the respective end face of base plate 3 and a horizontal plate 8, 8', secured to plate 6, 6', respectively, adjacent to its top edge.

Horizontal plates 8, 8' are connected to the top edges of vertically arranged, perforated stops 9, 9', respectively, which are seated on and attached to base plate 3. These stop plates form the stops for aligned left and right handed ways 10, 10' which slidably support push blocks 11, 11' arranged to actuate a lazy tongs squeezing arrangement 12 arranged between said blocks as will be later described.

The ways 10, 10' are of similar construction and include elongated rear way members 14, 14' and shorter front way members 15, 15' arranged in parallel relation to members 14, 15'. Each rear way member is seated on and secured to base plate 3 and abuts with its one end stop plates 9, 9', respectively, and with its other end a guiding saddle member 16 secured by screws 16' to base plate 3 crosswise thereof. The shorter front way members are also seated on and secured to base plate 3, abut with their one ends stop plate 9, 9', respectively, and have their other opposed ends axially spaced from each other. Rear way members 14, 14' are slotted at their inner ends and mount in their slotted portions guide blocks 17, 17', respectively, which include elongated slots 18, 18' for a purpose later to be described.

Lazy tongs squeezing arrangement 12 embodies a system of two aligned pairs 20, 21 of crossed bars 22, 22' and 23, 23', respectively, and two end bars 24, 24', each latter of which is arranged adjacent to one of said aligned pairs of crossed bars. The pairs of crossed bars 20, 21 have the central areas of their bars 22, 22' and 23, 23', respectively, pivotally connected with each other by headed pins 25, 25' which extend above the bars to engage loops and cross wires of sinuously corrugated wire springs placed on the squeezing arrangement. The opposed inner ends of bars 22 and 23 and bars 22' and 23' are pivoted to each other by headed pins 26, 26' which also extend above the bars. The outer ends of bars 22' and 23' are pivoted to end bars 24, 24' by headed pins 27, 27' and these end bars are coupled with the outer ends of bars 22, 23 by short link bars 28, 28' pivoted to bars 22, 23 by headed pins 29, 29' and to the central areas of bars 24, 24' by headed pins 30, 30'.

As lazy tongs squeezing arrangement 12 is pivotally secured to stationary saddle member 16 by pin 26, such

squeezing arrangement is subdivided in two symmetrically arranged squeezing portions 31, 31' which when actuated upon will be shifted jointly but in opposite directions with respect to each other. Squeezing portions 31, 31' are jointly guided by the pins 26' and 29, 29' which extend through elongated slot 32 in saddle member 14 and elongated slots 18, 18' in guide blocks 17, 17', slot 32 being rectangularly related to the axially aligned slots 18, 18'.

Actuating of the squeezing portions 31, 31' of the thus constructed lazy tongs arrangement is effected in one direction by a coil spring 33 connecting the lower ends of pin 30 with pin 34 mounted in base plate 3 and, in opposite direction by the push blocks 11, 11' guided in ways 10, 10' as previously described. Push blocks are coupled by longitudinally adjustable piston rods 35, 35' with hydraulic cylinders 36 supported by the cylinder hanger members 5, 5'. These piston rods include threaded portions 37 rotatably mounting adjusting nuts 38 and extend through circular openings 39 in stop plate 9, 9', respectively, which openings are smaller in diameter than nuts 38 to positively limit shifting movements of push blocks 11, 11', respectively.

In operation the device is first adjusted to effect in predetermined areas of a sinuously corrugated wire spring 40 the desired changes in the spacing of loop-connecting cross wires 41 by adjusting nuts 38 on piston rods 35, 35' and then spring 40 is placed on the device to align the respective loops of the predetermined area of the wire spring with the respective pins of the lazy tongs squeezing arrangement.

Thereafter hydraulic cylinders 36 are actuated by valve arrangement 42 to shift push blocks 11, 11' and actuate squeezing portions 31, 31' to effect reshaping of the loops of the wire springs for proper spacing of cross wires 41. Release of the valve arrangement inactivates the hydraulic cylinders 36 and permits removal of the wire spring from the device and thereafter by coil spring 33 return of the squeezing portions 31, 31' to their initial position.

Having thus described my invention, what I claim is:

In a device for changing the longitudinal spacing of successively connected left and right handed loops of sinuously corrugated wires, a frame, a lazy tongs lever arrangement including a plurality of elongated pins pivotally coupling the cross bars of each pair of bars to each other and pivotally coupling at one side edge of said arrangement the cross bars of adjoining pairs of bars to each other, one of said pins, the pin which couples two of the symmetrically opposed bars of the two adjacent pairs of the cross bars in the center portion of the lazy tongs lever arrangement, being non-shiftably supported in said frame, a pin coupling the other two of the symmetrically opposed bars of said two adjacent pairs of cross bars in the center portion of the lever arrangement, said last pin slidably engaged with said frame to effect by actuation of the lazy tongs lever arrangement straight movements of the pins at said one side edge and arcuate movements of the pins pivotally connecting the cross bars of each of said pairs of cross bars with each other, wire engaging head portions on said pins adapted to engage loops and loop connecting wire portions of sinuously corrugated wires placed on the device, and power operated push block means engaged with the free ends of the lazy tongs lever arrangement for actuating same.
